HARRY H. HANCOCK, OF BEACH BLUFF, MASSACHUSETTS; HENRY A. SAWYER ADMINISTRATOR OF SAID HARRY H. HANCOCK, DECEASED

VISE

Application filed August 31, 1927. Serial No. 216,754.

This invention relates to a vise, the principal object of which is to provide the base of a unitary vise with means for removably attaching it to a milling, drilling, punching, shaping, and other machines, and which vise is provided with means for quickly advancing one of its jaws up to the piece of work, as is generally the case with such unitary vises, and so as to bear on the work and possibly to grip it somewhat, but which improved vise is also provided with means for obtaining an additional advance adjustment of the movable jaw for the purpose of finally clinching and gripping the work, after the movable jaw has been thus primarily advanced, to hold the work with certainty in such an accurate, rigid position as cannot be obtained by the customary form of such vises, so that the improved vise, embodying the combined gripping features stated, is a self-contained unit which may be handled as such for attachment to or removal from a machine.

Heretofore the usual unitary vises have not had such provisions as just stated, whereas other so-called vises consist merely of jaws which are adjustable by bolts extending into the slotted beds of the machines and which are the equivalents of the bolts which are used to attach the usual unitary vises in position. Thus, such "so-called" vises are in a class by themselves and although they may have means for obtaining such a grip on the work as to hold it fairly rigid, they do not have the jaw advancing means of the usual unitary vises and cannot first engage the work by a quick advancing movement, nor can the jaw attaching bolts thereof be employed in that connection, as those bolts are not the equivalent of the preliminary jaw advancing means of the present invention. In fact, if such bolts were relied upon for obtaining a preliminary advance movement of the movable jaw, they could not be relied upon to obtain an engagement with the work which could be comparable with the quick engagement which can be obtained under the present invention, and it therefore follows that such so-called vises cannot cause the work to be gripped with the combined elements of quickness, reliability, ac-

curacy and rigidity as under the present invention.

With these and other objects in view, the present invention resides primarily in a vise comprising a movable jaw, means for preliminarily advancing the same up to the work to be gripped, and positive means for further advancing the jaw for finally gripping the work and for releasing the jaw from such final grip, such positive means being operable independently of the means for preliminarily advancing the movable jaw.

These being among the objects of the present invention, the same consists of certain features of construction and combinations of parts to be hereinafter described and then claimed with reference to the accompanying drawings illustrating a preferred embodiment of the invention, in which

Fig. 1 is a plan of the improved vise, the irregularity of the work and the complementary adjustment of the movable jaw being somewhat exaggerated for the sake of clearness;

Fig. 2 is a longitudinal section thereof on the line of the advancing spindle of the movable jaw, which is in a different position from that shown in Fig. 1;

Fig. 3 is a view of portions of the vise shown in the section of Fig. 2, the work not yet having been gripped;

Fig. 4 is a transverse section in the plane of the adjusting post of the movable jaw;

Fig. 5 is a transverse section on the line 5-5, Fig. 2, the movable jaw being shown in full lines in one position and in dotted lines in another position; and

Fig. 6 is a transverse section on the line 6-6, Fig. 2.

Referring to the drawings, the self-contained vise unit of the present invention is provided with a base 10 having a stationary abutment jaw 11 at one end and a stationary lug 12 at the other end. The machines to which the improved vise may be applied are usually provided with a number of grooves or ways, such as 13, in the bed 14. To adapt the device to the way 13 so that it may be attached and removed as a unit, the base of the vise is preferably provided with fastening

bolts 15 which are headed at their lower ends so as to under hand the overhanging portions of the way 13, whereby the vise may be adjusted along the bed of the machine as a unit 5 and the same held in adjusted position by the heads of the bolts engaged under the overhanging portions of the guide-way 13. To facilitate applying the bolts 15 to the base 10 of the unitary vise, the base is provided 10 with open notches 16 to receive the bolts whose upper ends are screw-threaded and provided with nuts for tightening up the bolts. Such bolts are commonly employed for setting unitary machine vises in the zone 15 in which a piece of work is to be gripped and worked.

The unitary vise is provided with a slide 17 and with a movable head block 18, the head or block 18 having a feather 19 which is adjustable in a transversely T-shaped slot or guide-way 20 in the base 10 of the vise, which slot extends toward the stationary jaw 11. The slide 17 is guided in the wider portion of slot or guide-way 20 and is attached to head 18 by 25 means of screws 21 which pass through the slide and enter the feather 19, whereby the slide and said head are rigidly secured together.

A rotary shaft or spindle 22 passes through 30 and is journaled in a bearing formed by the lug 12, said shaft being suitably held against longitudinal movement relatively to the said lug. The outer end of the shaft is provided with a hand-crank 23. This hand-crank is 35 preferably quite small so that the vise may be applied in any desired place on the machine inasmuch as the length of the lever furnished by the arm of the crank is only great enough to permit the desired power to be applied to 40 the shaft 22, which power need be only relatively small inasmuch as by the use of the hand-crank it is preferably intended only to supply sufficient power for preliminarily advancing, through the medium of screw-thread 45 24, the movable jaw to be later described. The movable head 18 is provided with a screw-threaded bore 25 with which engages the screw-threaded portion of the shaft 22.

A guide post 26 is screw-threaded at its 50 lower end and is threaded into that end of the slide 17 which projects beyond the head 18, so that a movement of the head 18 by the quick advancing movement produced by spindle 22 will correspondingly move the post 26. Opposing the stationary jaw 11 there is a wedge jaw 27, which is provided with a somewhat enlarged hole 28 which connects a recess 29 in the bottom of the jaw and a recess 30 in the top thereof, the recess 29, hole 28, and recess 60 30 being in alinement. The adjustable post 26 passes through the relatively enlarged hole 28 and the recesses 29 and 30, whereby the wedge jaw 27 is mounted upon the post. The movable head 18 of the unitary vise and the wedge jaw 27 thereof are provided with contacting

inclined surfaces 31, the slant of the inclined surfaces extending in a plane at an acute angle to the axis of the screw-threaded shaft or spindle 22.

A collar 32 is pinned rigidly to the post 26, 70 so as to be preferably positioned within the recess 29. A bushing ring 33 is set more or less loosely into the upper end of the recess 29, and the hole thereof is enlarged correspondingly with the enlarged hole 28 in the movable jaw 27, and is interposed between the jaw and the fixed collar 32. The surface 33^a of the ring 33 is convex and bears upon the adjacent surface of the fixed collar 32. The post 26 is provided within the recess 30 with a 75 flange or fixed collar 34, and the inner surface 34^a of said flange is convex and has bearing 80 upon the lower end wall of the recess 30, and hence on the movable jaw 27. It will thus be seen that the movable jaw is loosely held 85 upon the adjusting post 26, at least sufficient to allow some movement of the jaw laterally, and it will also be seen that by reason of this fact plus the fact that the bearing surfaces 33^a, 34^a are more or less convex, the movable jaw is adapted to be tilted with respect to its length, that is, it may be skewed with reference to the longitudinal axis of the screw spindle 22.

Whether or not the movable jaw may have 95 a movement askew of the line of the axis of the spindle 22, the said jaw may be positively adjusted either inwardly or outwardly by means of the adjusting post 26.

If the movable jaw is mounted so that it 100 may be tilted or skewed in position, it is desirable to provide means for producing such movements by the mere adjustment of the post 26. To that end a dovetailed member 35 is swiveled on a screw stud 36 which is fixed to the inclined surface of the head 18. The dovetailed member extends transversely of the inclined surface of head 18 and is received in a dovetail groove 37 in the inclined face of the movable jaw 27. If the movable jaw is 105 not mounted for a tilting or skewing movement, the dovetail member 35 may be rigidly fixed to the head 18.

The stationary jaw 11 and the wedge jaw 27 are respectively provided with hard metal 110 face-plates 38, 39, the said plates being rigidly secured to said jaws in any suitable manner, as by means of screws indicated in dotted lines in Fig. 1. A piece of work 40 to be operated upon by the machine to which the unitary vise is attached is held between the jaw plates 38, 39 in a manner to be described hereinafter.

The adjustable post 26 is provided at its outer end with a wrench head 41 to which a suitable wrench may be applied for the purpose of turning the post. The wrench head 41 extends into the outer recess 30 of the wedge jaw and does not project beyond the said jaw, so that it is enclosed entirely 115 within the said recess. In order to close the 120

recess 30 and to prevent chips, dirt, etc., from falling into it, a cover plate 42 is mounted on pivot screw 43 which is fixed in the top of the movable gripping jaw 27. Whenever 5 a wrench is to be applied to the wrench head 41 to turn and adjust the post 26, the cover 42 will be swung to one side to admit the wrench into the recess 30.

In the use of the improved unitary vise, 10 the piece of work 40 is placed between the opposing faces of the stationary jaw 11 and the wedge jaw 27. The hand crank 23 is then turned to more or less quickly advance the movable head 18 with the wedge jaw carried thereby toward the work, the slide 17 carrying the said jaw 27 simultaneously with the head, by reason of the said jaw being mounted upon the post 26. The head 18 and the jaw 27 are advanced until the hard 15 metal face 39 of the jaw is brought in the desired firm contact with the piece of work 40. This is the preliminary movement of the movable jaw 27 in order to engage the work between the jaws 11 and 27, and is more or less similar to the usual movement of advancing a movable jaw in previous unitary vises to grip the piece of work, except that such customary unitary vises are not provided with the improvements of the present 20 invention.

After the work has been preliminarily engaged, a wrench is applied to the wrench head of the adjustable post 26 and turned so as to turn the post and screw it more or 25 less into the slide 17, thereby causing the post flange 34 to forcibly bear upon the wedge jaw 27 and to cause the inclined surface of said jaw to move upon the correspondingly inclined surface of the movable 30 head 18, the jaw then partaking of a lateral movement to a slight extent toward the piece of work due to the presence of the enlarged hole 28 in the jaw. In this manner a wedging action is obtained and the movable jaw 27 is 35 caused to more firmly and positively grip the piece of work 40 than is accomplished by the advance feeding movement of a movable head or nut such as the head 18, as in the usual unitary vises, even though the entire 40 advance movement of the head and movable jaw is produced by turning a hand crank of more powerful leverage than is that of the preferably small hand crank 23. Thereby the piece of work 40 is firmly, rigidly, 45 positively and accurately gripped for machining, tooling, etc., and cannot shift from its thus rigidly gripped position. When the piece of work has been satisfactorily operated upon, the cover 42 having been closed in the meantime, 50 the cover is again opened and a wrench is again applied to the head 41 of the adjustable post and the latter is turned reversely, the fixed collar 32 of the post and the intervening bushing ring 33 causing the 55 movable jaw to be positively moved outward-

ly or raised and to release the piece of work from the additional grip provided by the movable wedging jaw. If the releasing movement of the wedge jaw is insufficient, as it might be, to entirely free the piece of work, depending upon how much pressure has been obtained by the turning of the hand-crank, the crank 23 is rotated reversely so as to withdraw the head 18 and the jaw 27 from the piece of work.

In cases where the piece of work does not have parallel faces which are to be gripped, and the faces are more or less irregular or inclined the one with respect to the other, it is desirable to provide the improved unitary vise with means whereby the movable jaw may be tilted longitudinally or skewed with respect to the line of the axis of the screw spindle 22, that is with respect to the line of the advancing gripping movement produced by the movable head 18. Such a movement may be obtained by reason of the swiveling of the pivotal member 35, and the freedom of movement permitted at the bearing surfaces between the movable jaw and the post. In Figs. 1 and 5 the movable jaw is shown as having been tilted askew of the longitudinal axis of the advancing spindle 22, and it will be seen that when an irregular piece of work such as referred to is being gripped by the additional gripping action of the movable jaw 27, the inward adjustment of the adjustable post 26 and the swiveling movement of the dovetail member 35 will permit the movable jaw to rock upon the convex surface of the flange 34 and the convex surface of the bushing ring 33 to rock upon the fixed collar 32 of the post.

A very important feature of the present invention is that by means of the improved wedge jaw in unitary vises, the work to be clamped is forced inwardly toward the base of the vise or to a parallel bar which it is sometimes necessary to place under the work to bring its outer surface beyond the jaws of the vise. This is an important function performed by the wedge jaw of the improved unitary vise, inasmuch as with the unitary vises now in use it is sometimes difficult to firmly seat the work at the bottom between the gripping jaws. The usual method is to pound the work down with a lead mallet or hammer, but such method consumes valuable time; it sometimes mars the surface of the work and it is not good for the vise.

It is obvious that the invention herein described and illustrated in the drawings is susceptible of various modifications and the invention is not limited except as defined in the appended claims.

What I claim as new is:

1. In a vise, the combination of two jaws, a movable head for advancing one of the jaws toward the other jaw to preliminarily engage

the work, the head having an inclined end surface, means for mounting the movable jaw on the inclined surface of the head for a tilting movement, and means for imparting an additional gripping movement to the said movable jaw relatively to the movable head.

5 2. In a vise, the combination of two jaws, a movable head supporting and for advancing one of the jaws toward the other jaw to preliminarily engage the work, the head and its jaw having mutual bearing surfaces out of parallel with the gripping plane of the jaws, a swivel for connecting the movable jaw with the head, and means for adjusting the movable jaw relatively to said head.

10 3. In a vise, the combination of two jaws, a movable head for advancing one of the jaws toward the other jaw to preliminarily engage the work, the head and its jaw having mutual bearing surfaces in a plane inclined to the gripping plane of the jaws, a swivel on one of the inclined surfaces, a sliding connection between the swivel and the member having the other inclined surface, and means for 15 adjusting the movable jaw relatively to said head.

15 4. In a vise, the combination of a base, a jaw carried thereby, a head movable on the base, a longitudinally adjustable post carried by the head and between the head and said jaw, and a wedging jaw opposing aforesaid jaw and abutting the head, the wedging jaw carried one way or the other by the longitudinal movement of the post, and having 20 an enlarged hole for passage of said post and to allow movement of the wedging jaw laterally of the post.

25 5. In a vise, the combination of a base, a jaw carried thereby, a head on the base, and a movable jaw opposing aforesaid jaw and provided with a surface inclined upwardly and away from aforesaid jaw, and the head having a surface inclined correspondingly to the inclined surface of the movable jaw, 30 said surfaces bearing one on the other, and guiding means supported by the head and on which the movable jaw is guided and rockably mounted.

35 6. In a vise, the combination of a base, a jaw carried thereby, a head, a slide carrying said head and guided on the base, means for longitudinally moving the slide and head toward said jaw, said means being separate from the base-guide, a post adjustably supported by the slide, between said jaw and the head, and a movable jaw on the post, the post having means for adjusting the movable 40 jaw toward the gripped work independently of the head.

45 60 HARRY H. HANCOCK.
